[57] **CLAIM**

The ornamental design of a frame for battery electrodes with insulating intermediate support, as shown.

DESCRIPTION

FIG. 1 is a perspective front view of a frame for battery electrodes with insulating intermediate support;

FIG. 2 is a perspective back view of the frame for battery electrodes as shown in FIG. 1;

FIG. 3 is a top view of the frame for battery electrodes as shown in FIGS. 1 and 2;

FIG. 4 is a bottom view of the frame for battery electrodes as shown in FIGS. 1 and 2.

UNITED STATES PATENT OFFICE
CERTIFICATE OF CORRECTION

Patent No. Des. 243,859 Dated March 29, 1977

Inventor(s) Leif Erik Sköld

It is certified that error appears in the above-identified patent and that said Letters Patent are hereby corrected as shown below:

In the heading of the patent [73] and [30] should read as follows:

-- [73] Assignee: Svenska Utvecklingsaktibolaget (SU)
Swedish National Development Co,
Stockholm, Sweden--

-- [30] Foreign Application Priority Data

June 18, 1975 Sweden.....1258/75--.

Signed and Sealed this

Fourteenth Day of June 1977

[SEAL]
